UNITED STATES PATENT OFFICE

FREDERICK W. VODOZ, OF WILMETTE, ILLINOIS, ASSIGNOR TO GOODMAN MANUFACTURING COMPANY, OF CHICAGO, ILLINOIS, A CORPORATION OF ILLINOIS

MINING MACHINE

Application filed November 5, 1927, Serial No. 231,213. Renewed October 21, 1931.

This invention relates to improvements in mining machines and more particularly to machines of the truck mounted type having a projecting kerf cutting element adjustable 5 in varying positions relative to the main frame for making various vertical or shearing cuts.

More specifically, the present invention relates to improvements in a type of mining 10 machine provided with trunnions disposed both forwardly and rearwardly of the transverse axis of rotation of a cutter bar pivotally mounted on said head, and having means for raising and lowering said cutter bar, consisting of a pair of vertically disposed screw devices mounted forwardly of the foremost trunnion bearings of the cutter head.

In the present invention I provide an improved form of operative connection between 20 the screw devices at the front end of the frame and the main drive gearing carried on the body of the machine frame whereby greater simplicity and flexibility of operation is afforded.

25 The invention may be best understood by reference to the accompanying drawings wherein:

Figure 1 is a vertical section following generally the longitudinal center line of the machine and showing the cutter bar in substantially horizontal position at one side of the frame;

Figure 2 is a fragmentary plan view of the front part of the frame with parts broken away to show the operating connections to the raising and lowering devices, forming the principal feature of the present invention;

Figure 3 is an enlarged sectional view taken on line 3-3 of Figure 2; and

40 Figure 4 is a detailed section taken on line 4-4 of Figure 2.

The main elements of the machine include a main frame 10 having a forwardly projecting rigid supporting member 26 at its front end. The machine is moved from place to place and into angular cutting position by suitable traction means, herein comprising a pair of continuous tread mechanisms generally indicated at 13, 13 although it is manifest 45 that a machine of this character might also

be mounted for movement on track guided truck wheels, if desired. A cutter head indicated generally at 20 has a cutter bar 14 pivotally mounted thereon which cutter bar may carry an endless cutter chain about its periphery in a usual manner and is coaxial with a cutter chain drive shaft 29. A pair of trunnion bearings are provided for the cutter head 20. One of these bearings comprises a cylindrical bearing 22 formed near the front 55 of the main frame 10 in which a cylindrical neck 21 is journaled. An auxiliary bearing member 23 is connected to forwardly extending arms 24, 24, forming part of the cutter head 20 and is journaled in a cylindrical outboard support or bearing 25 upstanding on the rigid supporting member 26.

The arrangement is such that the cutter bar 14 and cutter head 20 may be bodily rotated relative to the main frame on an axis 60 extending longitudinally of the latter from a point at one side of the frame through an arc extending over the top of the frame to a corresponding position at the opposite side of the frame on the bearings 22 and 23 forwardly and rearwardly of the axis of the cutter bar 14 in a manner which will hereinafter be 65 more clearly described.

The cutter bar 14 is pivotally mounted on the cutter head 20 for swinging movement 70 in a plane parallel to the axis of rotation of said cutter head by means of a support 18, formed integral with a transverse yoke 30 which extends across the front of said cutter head. A rod 33 is fixed centrally of the yoke 75 30 and projects forwardly therefrom through the auxiliary bearing member 23. A sleeve 34 is journaled on the forward end of the rod 33 and has a pair of oppositely disposed pins 35, 35, forming pivotal connection with 80 a pair of vertically disposed links 36, 36. These links are connected at their upper ends by a tie rod 37 and are pivotally secured at their lower ends on a shaft 38 carried by a cross member generally indicated at 39 85 95 and best shown in Figures 1 and 3 which is not described in detail but is only described in so far as is necessary to illustrate my present invention.

Power connections are provided for posi- 100

tively swinging the cutter bar on its pivotal axis by means of a pair of screw shafts 40, 40, having threaded connection at opposite ends of the cross member 39. These screw members have bearing at their upper ends in brackets 41, 41, projecting forwardly from the cylindrical bearing support 25 and their lower ends in the forwardly projecting supporting member 26.

Referring now to the novel features of the present invention, which relates to the driving connections for the screw shafts 40, 40, I provide each of the screw shafts with chain sprockets 42, 42, disposed within the supporting member 26 and a co-operating drive sprocket 43 disposed on vertical shaft 44, having suitable bearings 44^a, 44^a, in the main frame and preferably disposed rearwardly of the pivotal axis of the cutter bar 14 in the cutter head 20. An endless drive chain 45 is trained about sprockets 42, 42, and the drive sprocket 43, as is best shown in Figures 1 and 2. An idler tension adjusting sprocket 46 is also provided intermediate the sprockets 42, 42. This sprocket is preferably mounted on a shaft 46^a carried in a longitudinally adjustable support 47 slideable along guides 48, 48, formed on the under surface of the supporting member 26, as best shown in detail in Figures 3 and 4. Longitudinal adjustment of the idler sprocket 46 is afforded through a screw shaft 49 threaded in enlarged hub portion 49^a on the upper end of shaft 46^a. By manipulation of the screw shaft 49 the idler sprocket 46 may be shifted to adjust the tension of the drive chain 45, as desired.

On account of the relatively restricted shape of the projecting supporting member 26, the chain 45 is also trained over idler rollers 45^a, 45^a, at opposite sides of the frame, as best shown in Figure 2.

Referring now to the power connections for performing the various operations of the machine above described, I provide a motor 50, preferably mounted adjacent the rear of the main frame 10 and having a driving pinion 51 meshed with a gear 52 on a longitudinal shaft 53. This shaft is connected for driving the cutter chain through a bevel pinion 55 and bevel gear 56 keyed on the shaft 29. A cutter chain sprocket of an ordinary construction (not shown herein since it is no part of my invention) is mounted on the outer end of the shaft 29 to drive the cutter chain (not shown).

The driving connections for rotating the cutter head 20 in its trunnion bearings 22 and 23 include a pinion 57 on the shaft 53 meshing with a gear 58 keyed to a sleeve 59 on a shaft 63. The sleeve 59 forms a part of a planetary gear reduction device 62 of the type widely used in mining construction, details of which need not herein be described. The planetary gear reduction device 62 is

mounted on and is adapted to drive the shaft 63 at a plurality of speeds in a usual manner (not shown), which shaft extends forwardly through a bearing support 64 and has a beveled gear 65 at its forward end meshing with a beveled gear 66 on a transverse shaft 67. The beveled gear 66 is loosely mounted on the transverse shaft 67 and is operatively connected therewith by clutch means of an ordinary construction (not shown). A worm 68 is keyed on the transverse shaft 67 and meshes with a worm gear 69 secured to and concentric with the neck 21 of the cutter head 20. The worm 68 and worm gear 69 are of the self-locking type so the cutter head will be locked for cutting operations in any position to which it may be rotated.

Reversible driving connections for rotating the elevating screw shafts 40 are taken off the shaft 63 through pinions 90 and 91 and a spur gear 92. The pinion 91 is driven from the pinion 90 and is meshed with the gear 92 which is keyed on a sleeve 93 loosely mounted on a longitudinal shaft 94. The sleeve 93 is operatively connected to the shaft 94 by means of a suitable jaw clutch 95 of an ordinary construction. A beveled gear 96 is keyed on the forward end of the shaft 94 and is meshed with mitre gears 97 and 98 loosely mounted on the upright shaft 44 and selectively engageable therewith by means of an intermediate reversing clutch member 99 so the drive chain 45 may be driven in either direction relative to the shaft 94 or disconnected therefrom when the clutch member 99 is held in neutral position, as best shown in Figure 1.

Through the drive connections just described, the screw shafts 40 may be rotated at either high or low speeds controlled by the planetary gear reduction device 62 and in reverse directions without reversing the motor to raise or lower the cross member 39 and thus pivotally move the cutter bar 14 about the axis of the shaft 29 for feeding said cutter bar vertically in the coal.

Means for driving the traction devices 13, 13 are also provided herein consisting of a beveled pinion 105 keyed on the rearward end of the shaft 94 and meshed with a beveled gear 106 on a transverse shaft 107 at the rearward end of the machine frame. A pinion 108 on the opposite side of the planetary gear reduction device 62 from the pinion 90 is keyed on the shaft 63 and drives a spur gear 109 keyed on a sleeve 110 loosely mounted on the shaft 94. A suitable clutch member, indicated by reference character 111, is provided to selectively connect the sleeve 110 and spur gear 109 to the shaft 94 for driving said shaft. It may be seen that the shaft 94 may be driven in one direction through the pinion 108 and spur gear 109, or in an opposite direction through the pinions 90 and 91 and the spur gear 92, so the machine may be

driven in opposite directions without reversing the motor and independently of the screw shafts 40. Suitable driving and control connections are provided between the shaft 107 and the endless treads 13, 13, details of which need not be described herein as they form no part of the present invention.

Although I have shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

I claim as my invention:

1. In a mining machine, a main frame, a motor, a cutter head mounted for rotation about an axis parallel to the longitudinal axis of said main frame including a cutting element offset from and mounted for pivotal swinging movement in planes substantially parallel with the axis of rotation of said cutter head, coacting power means including screw devices carried on said main frame in advance of said cutter head for swinging said cutting element, and operative connections between said motor and said screw devices including a chain drive for said screw devices extending rearwardly beneath said cutter head, and a drive sprocket therefor on said main frame.

2. In a mining machine, a main frame, a motor, a cutter head mounted for rotation about an axis parallel to the longitudinal axis of said main frame including a cutting element offset from and mounted for pivotal swinging movement in planes substantially parallel with the axis of rotation of said cutter head, coacting power means including screw devices carried on said main frame in advance of said cutter head for swinging said cutting element, operative connections between said motor and said screw devices including a chain drive for said screw devices extending rearwardly beneath said cutter head, a drive sprocket therefor on said main frame, and reversible power connections mounted concentrically with said drive sprocket.

3. In a mining machine, a main frame, a motor, a cutter head mounted for rotation about an axis parallel to the longitudinal axis of said main frame including a cutting element offset from and mounted for pivotal swinging movement in planes substantially parallel with the axis of rotation of said cutter head, coacting power means including screw devices carried on said main frame in advance of said cutter head for swinging said cutting element, and operative connections between said motor and said screw devices including a single continuous chain drive op-

eratively connected with all of said screw devices and extending rearwardly beneath said cutter head, and a drive sprocket therefor on said main frame.

4. In a mining machine, a main frame, a motor, a cutter head mounted for rotation about an axis parallel to the longitudinal axis of said main frame including a cutting element offset from and mounted for pivotal swinging movement in planes substantially parallel with the axis of rotation of said cutter head, coacting power means including a pair of screw devices carried on said main frame in advance of said cutter head and on opposite sides of the axis of rotation thereof for swinging said cutting element, and operative connections between said motor and said screw devices including a single continuous chain drive operatively connected with both of said screw devices and extending rearwardly beneath said cutter head, and a drive sprocket therefor on said main frame.

5. In a mining machine, a main frame, a motor, cutting mechanism therefor including a sprocket, a cutter arm pivotally mounted on said frame for pivotal movement about the axis of said sprocket, means carried on said main frame in advance of said sprocket for moving said cutter arm about its axis of pivotal connection to said frame, and operative connections between said motor and said means for pivotally moving said cutter arm including an endless chain drive movable in a closed orbital path and operatively connectible with said means for pivotally moving said cutter arm, said endless chain extending rearwardly from said means beneath said cutter arm.

6. In a mining machine, a main frame, a motor, cutting mechanism therefor including a sprocket, a cutter arm pivotally mounted on said frame for pivotal movement about the axis of said sprocket, means carried on said main frame in advance of said sprocket for moving said cutter arm about its axis of pivotal connection to said frame, and operative connections between said motor and said means for pivotally moving said cutter arm including a chain drive for said means extending rearwardly from said means beneath said cutter arm, a drive sprocket therefor on said main frame, and reversible power connections mounted concentrically with said drive sprocket.

7. In a mining machine, a main frame, a motor, cutting mechanism therefor including a sprocket, a cutter arm pivotally mounted on said frame for pivotal movement about the axis of said sprocket, coacting power means including a screw device carried on said main frame in advance of said sprocket for swinging said cutter arm, and operative connections between said motor and said screw device including a chain drive for said screw

device extending rearwardly beneath said cutter arm, and a drive sprocket therefor on said main frame.

8. In a mining machine, a main frame, a motor, cutting mechanism therefor including a sprocket, a cutter arm pivotally mounted on said frame for pivotal movement about the axis of said sprocket, coacting power means including a screw device carried on said main frame in advance of said sprocket for swinging said cutter arm and operative connections between said motor and said screw device including a chain drive for said screw device extending rearwardly beneath said cutter arm, a drive sprocket therefor on said main frame and reversible power connections mounted concentrically with said drive sprocket.

9. In a mining machine, a main frame, a motor, cutting mechanism therefor including a sprocket, a cutter arm pivotally mounted on said frame for pivotal movement about the axis of said sprocket, coacting power means including screw devices carried on said main frame in advance of said sprocket for swinging said cutter arm and operative connections between said motor and said screw devices including a chain drive for said screw devices extending rearwardly between said cutter arm, and a drive sprocket therefor on said main frame.

10. In a mining machine, a main frame, a motor, cutting mechanism therefor including a sprocket, a cutter arm pivotally mounted on said frame for pivotal movement about the axis of said sprocket, coacting power means including screw devices carried on said main frame in advance of said sprocket for swinging said cutter arm, and operative connections between said motor and said screw devices including a chain drive for said screw devices extending rearwardly beneath said cutter arm, a drive sprocket therefor on said main frame and reversible power connections mounted concentrically with said drive sprocket.

11. In a mining machine, a main frame, a motor, cutting mechanism therefor including a sprocket, a cutter arm pivotally mounted on said frame for pivotal movement about the axis of said sprocket, coacting power means including screw devices carried on said main frame in advance of said sprocket for swinging said cutter arm, and operative connections between said motor and said screw devices including a single continuous chain drive operatively connected with all of said screw devices and extending rearwardly beneath said cutter arm, and a drive sprocket therefor on said main frame.

12. In a mining machine, a main frame, a motor, cutting mechanism therefor including a sprocket, a cutter arm pivotally mounted on said frame for pivotal movement about the axis of said sprocket, coacting power means

including screw devices carried on said main frame in advance of said sprocket for swinging said cutter arm and operative connections between said motor and said screw devices including a single continuous chain drive operatively connected with all of said screw devices and extending rearwardly beneath said cutter arm, a drive sprocket therefor on said main frame and reversible power connections mounted concentrically with said drive sprocket.

Signed at Chicago, in the county of Cook and State of Illinois, this 26th day of October, A. D. 1927.

FREDERICK W. VODOZ.
